(57) **CLAIM**

The ornamental design for an area light as shown and described.

DESCRIPTION

FIG. 1 is a perspective view of an area light according to our new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top elevation view thereof; and

FIG. 8 is a bottom plan view thereof.

FIG. 9 is a perspective view of an area light according to another embodiment of our new design;

FIG. 10 is another perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top elevation view thereof; and,

FIG. 16 is a bottom plan view thereof.

The broken lines in FIGS. 2, 4, 5, 8, 9, 10, 13, and 16 represent portions of the article that are not considered part of the claimed design.
